The ornamental design for a light, as shown and described.

DESCRIPTION

FIG. 1 is a top, front, left perspective view of a light showing our new design;

FIG. 2 is a bottom, back, right perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof;

FIG. 8 is a bottom plan view thereof; and,

FIG. 9 is a top, front, left perspective view of the light coupled to a strap.

The dash-dash broken lines shown in the drawings represent parts of the light that form no part of the claimed design. In FIG. 9, the dash-dash broken lines also represent the unclaimed strap. The dot-dash broken lines shown in the drawings represent the unclaimed boundary of the claimed design.
